UNITED STATES PATENT OFFICE.

ISAAC COMONN, OF NEW YORK, N. Y.

DESIGN FOR A MUFF.

SPECIFICATION forming part of Design No. 29,256, dated August 23, 1898.

Application filed July 27, 1898. Serial No. 687,041. Term of patent 7 years.

To all whom it may concern:

Be it known that I, ISAAC COMONN, a citizen of the United States, residing at New York, borough of Manhattan, State of New York, have invented and produced a new and original Design for Muffs, of which the following is a specification, reference being had to the accompanying drawing, showing a part thereof.

5 The leading feature of my design consists of an elliptic shield and a bow-shaped ornament below the shield.

10 A is the body of the muff, and B the band, provided with a bow C.

D is the elliptic shield, located at the upper part of the muff, and E a bow-shaped ornament arranged below the shield.

What I claim is—

15 The design for a muff, as herein shown and described.

In testimony that I claim the foregoing as my invention I have signed my name in presence of two subscribing witnesses.

ISAAC COMONN.
